Primary Examiner—Gary D. Watson

[57] CLAIM

The ornamental design for a chair, as shown and described.

DESCRIPTION

FIG. 1 is a perspective view of a chair showing my new design;

FIG. 2 is a front elevational view thereof;

FIG. 3 is a rear elevational view thereof;

FIG. 4 is a right side elevational view, the left side being a mirror image thereof;

FIG. 5 is a top plan view thereof; and,

FIG. 6 is a bottom plan view thereof.

The fragmented depiction of mesh-like structure within the upper portion of the backrest in FIG. 1 is understood to be continuous throughout the implied area. FIG. 1 has been shown on an enlarged scale with respect to the other views.
